UNITED STATES PATENT OFFICE.

SVEND BARFOED, OF OAKLAND, CALIFORNIA, ASSIGNOR OF TWO-FIFTHS TO OTIS
GIBSON, OF SAN FRANCISCO, CALIFORNIA.

HIGH-TENSION INSULATOR.

1,173,994.

Specification of Letters Patent. Patented Feb. 29, 1916.

Application filed August 18, 1914. Serial No. 857,315.

To all whom it may concern:

Be it known that I, SVEND BARFOED, a subject of the King of Denmark, residing at Oakland, in the county of Alameda and State of California, have invented new and useful Improvements in High-Tension Insulators, of which the following is a specification.

This invention relates to a high tension insulator.

In long-distance transmission of electric currents, it is common to employ very high voltage in order to transmit the required power with minimum size of line conductors.

15 In the insulation of high potentials of sixty thousand to one hundred thousand volts and over, serious difficulties arise by reason of "leakage" or "creepage" of the electricity over the surface of the insulators.

20 This "creepage" is principally due to dust and moisture upon the surface of the insulators, which constitutes a film for the conduction of electricity or minute conducting areas between which static discharges

25 may take place. (A source of failure in the common type of high voltage insulators is due to minute haircracks in the porcelain or glass of the insulators. Electrically conductive paths are fused through these cracks

30 resulting in the destruction of the insulators.) These cracks are caused by certain stresses set up in ordinary insulators by bolts and other types of fastening devices which are generally secured in the insulator

35 by means of cement. The relative expansion of cement, iron and porcelain being quite dissimilar, naturally causes excessive strains within the insulator, producing the hair-like cracks.

40 The object of the present invention is to provide a form of insulator fastening, which is so positioned and secured that the temperature changes will not produce stress in the body of the insulator, thereby overcoming the difficulties previously mentioned.

45 Other objects will hereinafter appear.

Figure 1 shows the application of the invention. Fig. 2 is a longitudinal section through the insulator. Fig. 3 is a detail view of same showing the fastening means. Fig. 4 is a perspective view of the securing clip. Fig. 5 is a cross section on line 5—5 of Fig. 3.

55 A indicates an electric insulator whereby a wire or conductor 2 may be suspended from the tower or post 3. The insulator

proper consists of a spool or tube-shaped body of suitable length constructed of porcelain or like material, having a plurality of deep annular parallel corrugations 5, and 60 high ridges 6 formed on its exterior surface. The insulator proper is girdled centrally by a clamp 7, which may be fastened by a bolt or rivet 8, to the suspension arm 9 of post or tower 3.

65

For thoroughly insulating high tension lines, a plurality of insulators are suspended one from the other, as indicated in Fig. 1, this being accomplished by a central beam 10, which is secured at 11 in the center of 70 each insulator tube, and upon the outer ends of beam 10 are mounted suspension links 12, by which one insulator is hung from the other.

70

Suitably secured to the center portion of 75 beam 10 by means of a rivet 13, or the like, is a pair of clip members. These clip members are provided with four arms, 14, 15, 16 and 17, arms 14 and 15 being turned up as at 18, after the beam is inserted, to secure it in position within the insulator. Surrounding the beam and forming a packing or cushion between the interior of the insulator and the beam proper, is a lining of compressible fiber or like material. This 80 fiber lining is divided into two sections, 19 and 22, as indicated in Fig. 5, and this is held in position by arms 16 and 17, which extend into recesses 16' and 17' formed in the ends of the fiber sections.

90

The compressible lining interposed between the insulator and the beam 10, absorbs all stress caused by the difference in expansion between the iron beam and the insulator proper, thus relieving the insulator from stress of this nature. The fiber cushion, furthermore, absorbs all the mechanical force transmitted through it, so that only compressive stresses occur. The body of the insulator is thus entirely relieved of the stress produced by temperature changes and the difficulties heretofore mentioned are thus entirely overcome.

95

The metal clips by which the beam is secured within the insulator, provide a 100 means by which the insulators may be easily and quickly connected or disconnected as the case may be.

100

A compressible fiber lining 21 may be inserted between clamp 7 and the exterior of 110 the insulator.

The material and finish of the several

2
parts of the device are such as the experience and judgment of the manufacturer may dictate.

I wish it understood that various changes in form, proportions and minor details of construction may be resorted to within the scope of the appendant claims, and that I do not wish to limit myself to the specific design and construction here shown.

10 Having thus described my invention, what I claim and desire to secure by Letters Patent, is

15 1. In a high potential insulator, a hollow insulating member, a beam extending through the insulator, a compressible lining interposed between the beam and the interior of the insulator, and clips secured to the beam having bendable arms formed thereon to secure the beam within the insulator.

20 2. In a high potential insulator, a hollow insulating member, a beam extending through the insulator, an annular seat formed within the insulator, a compressible lining interposed between the beam and said seat, and clip members secured to the beam having bendable arms formed thereon engageable with the sides of the annular seat to secure the beam within the insulator.

25 3. In a high potential insulator, a hollow insulating member, a beam extending through the insulator, and clips secured to the beam to secure the beam within the insulator.

30 4. In a high potential insulator, a hollow insulating member, a beam extending through the insulator, an annular seat formed within the insulator, a compressible lining interposed between the beam and

said seat, clip members secured to the beam having bendable arms formed thereon engageable with the sides of the annular seat to secure the beam within the insulator, and secondary arms on the clips to secure the compressible lining in position. 40

45 5. In a high potential insulator, a tubular-shaped insulator, an annular comparatively narrow seat formed interiorly of the insulator, a beam extending through the insulator, and a compressible lining interposed between the annular seat and beam.

50 6. In a high potential insulator, a tubular-shaped insulator, an annular comparatively narrow seat formed interiorly of the insulator, a beam extending through the insulator, a compressible lining interposed between the annular seat and the beam, and means for securing the beam and lining against endwise movement in the annular seat. 55

60 7. In a high potential insulator, a tubular-shaped insulator, an annular comparatively narrow seat formed interiorly of the insulator, a beam extending through the insulator, a compressible lining interposed between the annular seat and beam, and means for securing the beam and lining against endwise movement in the annular seat, said means comprising clip-like fingers secured on the beam and engageable with the sides 65 of the annular seat.

70 In testimony whereof I have hereunto set my hand in the presence of two subscribing witnesses.

SVEND BARFOED.
